Frederick A. Cleveland, INVENTOR,

BY HIS ATTORNEY Lewis J. Doohale

UNITED STATES PATENT OFFICE.

FREDERICK A. CLEVELAND, OF NEW YORK, N. Y.

BINDER.

No. 809,494.

Specification of Letters Patent.

Patented Jan. 9, 1906.

Application filed July 7, 1905. Serial No. 268,659.

To all whom it may concern:

Be it known that I, FREDERICK A. CLEVELAND, a citizen of the United States, and a resident of New York, in the county of New York and State of New York, have invented 5 certain new and useful Improvements in Binders, of which the following is a specification.

This invention relates to a device which 10 may be applied to binders of the loose-leaf type, the object being to provide a device of simple construction which may be used in connection with covers or binders of this class which may be easily operated and 15 which will be positive in its action. The use of binders of this description is well understood and it is not thought necessary to enter into an explanation of their operation further than to state the principal requirement, 20 which is that any number of pages or leaves may be inserted, replaced, or taken out without disturbing the remaining leaves.

The object of my invention is to provide a device which shall meet this requirement and 25 accomplish the desired result by the use of a simple locking mechanism which does not require separate keys or other devices to operate the same and which shall be self-contained and operated by turning the book on 30 one side to lock the covers in any desired position and to release the same by simply reversing the position of the book. To accomplish this result, I provide an upper and lower clamping-section, which may be attached to the covers of the binder. These 35 clamping-sections are normally held apart by the action of springs contained in telescoping members attached to said clamping-sections in the usual manner. Attached to one of 40 these clamping-sections, preferably the upper, I provide a post which carries a rotary pawl or dog, which is adapted to engage projections on the interior of a coöperating post or casing, which is secured to the lower 45 clamping-section. This latter post or casing is adapted to telescope over the post carrying the pawl or dog. The construction of these parts is such that when the clamping-sections and attached covers are in the position 50 shown in the drawings a free inward movement is permitted and the leaves may be clamped and held between the clamping-sections by pressing the upper cover down. The pawl or dog will engage the projections 55 upon the outer post or casing and so hold the

parts in position. An auxiliary weight cooperates with the rotary pawl or dog to hold the same in its operative position when the parts are in the position just described. When the position of the covers is reversed, 60 this auxiliary weight drops out of engagement with the pawl and allows the same to rotate out of engagement with the casing, and so permits the clamping members to be separated.

The construction and operation of the device will be more fully explained in connection with the drawings accompanying this specification.

Figure 1 is a perspective side elevation of a 7c pair of clamping-sections or binder-frames with the covers and leaves of the book omitted. Fig. 2 is an enlarged side elevation in section of a post and casing carrying a locking mechanism. Fig. 3 is an enlarged 75 side elevation and detail view of the post carrying the pawl or dog. Fig. 4 is an enlarged side elevation in section of a post and casing, showing a modification of the rotary pawl forming a part of the locking mechanism. 8c

In Fig. 1, at 1 and 2, is shown an upper and lower clamping-section, respectively, which may be attached by any suitable means to the cover of the binder, or, if preferred, the covers themselves may form the clamping-sections and have the locking device attached directly thereto. At 3 3 are shown telescoping members containing springs which operate normally to separate the clamping members 1 and 2 when not held in position by 85 means of the locking mechanism carried by the post 4 and casing 7. The operation of this locking mechanism is on the principle of a pawl-and-ratchet device, the distinguishing features of this device being in the construction and mode of operation of the rotary pawl and an auxiliary locking-weight, which 90 operates in conjunction therewith to hold this pawl in such positions that the outer end thereof will engage projections on the interior of the casing 7 when the covers are in one position, and when the covers are reversed in position this auxiliary weight drops out of engagement with the pawl, rendering 95 the same inoperative. 100

At 4 is shown a post, which is secured to the upper clamping member 1 by any suitable means and preferably in such a manner that the same may be rotated. This may be done by socketing the post 4 in the clamping 110

member 1 and holding the same in such a position by means of an ordinary flat-headed screw, as shown in the drawings. This screw may be secured in the post 4 by any suitable means, and by using an ordinary screw-driver in the slot thereof the post may be rotated as desired. At the lower end of this post 4 is provided a recess or slot in which is carried a pawl 5. This pawl is pivotally supported in said slot at 6. A chamber 9 is also provided at the lower end of the post 4 in proximity to the recess carrying the pawl 5. In this chamber is carried an auxiliary weight 8, which when the members are in the position shown in the drawings will drop to the lower end of the chamber 9, in which position it engages the pawl 5 and prevents the same from rotating in one direction, and so locks or holds said pawl in a position such that the outer end thereof engages the projections on the interior of the casing 7.

The casing 7 is secured to the lower clamping member 2 by any suitable means and is adapted to telescope over the post 4. The inner surface of this casing is provided with serrations or projections, which are preferably in the form of a screw-thread or spiral. The object of providing projections of this kind is to allow of a further tightening of the clamping members by rotating the post 4 and the attached pawl, as already described.

When the parts are in the position shown, the separation of the clamping members is prevented, as the outer end of the pawl engages the projections already described, and as the pawl is prevented from rotating in the direction corresponding to an outward movement of the post and casing by means of the auxiliary weight 8 the members are held in this position. When the position of the covers is reversed, the auxiliary weight 8 will drop to the opposite end of its chamber 9. The pawl 5 is now free to rotate on its pivot 6, and consequently the post and casing, with the attached clamping members, may be separated. The recess or slot in which the pawl is located has the upper portion thereof so formed as to provide a stop to limit the movement of the pawl in this direction, and consequently it is prevented from falling into such position that the reversal of the covers to the position shown would fail to bring the several parts into operative position already described.

In Fig. 4 is shown a modification of the pawl and locking mechanism. The operation of the parts in this construction is the same as the one already described, and the same description may be applied thereto, using the reference-number 5' for the pawl, 6' for the pivot, 8' for the auxiliary weight, and 9' for the chamber for said weight. The outer end of the pawl in this construction is provided with a plurality of projections corresponding to the threaded interior surface of the casing 7. The outer ends of these projections or

teeth may be arranged on the arc of the circle to permit the rotation of the pawl 5' around its pivot 6'.

It will be noted that the device herein shown and described as an illustration of an operative embodiment of my invention is composed of a very small number of parts and that such parts are of a simple construction and may be easily and cheaply manufactured. It will be also noted that the device when assembled is very compact in form and that the operating parts are self-contained within the same.

I do not confine myself, however, to the exact details of construction shown and described, as it will be evident that various modifications and changes may be made therein to adapt the device to its several uses without departing from the scope of my invention.

What I claim is—

1. In a binder, the combination of a pair of clamping members, a post attached to one of said members, an oscillatory pawl or dog carried by said post and adapted to engage the inner surface of a casing, a casing secured to the other of said clamping members and adapted to telescope over said post, an auxiliary weight coöperating with said pawl or dog to lock the same in engagement with said casing, substantially as described.

2. In a binder, the combination of a pair of clamping members, a post having a slot at the lower end thereof attached to one of said clamping members, an oscillatory pawl or dog carried by said post in said slot and adapted to engage the inner surface of a casing, a casing secured to the other of said clamping members and adapted to telescope over said post, an auxiliary weight coöperating with said pawl or dog to lock the same in engagement with said casing, substantially as described.

3. In a binder, the combination of a pair of clamping members, a post having a slot at the lower end thereof attached to one of said clamping members, an oscillatory pawl or dog carried by said post in said slot in such a manner that the movement thereof is limited by an auxiliary weight in one direction so that the outer end of said pawl will engage the inner surface of a casing, a casing secured to the other of said clamping members and adapted to telescope over said post, an auxiliary weight coöperating with said pawl or dog to hold the same in engagement with said casing, substantially as described.

4. In a binder, the combination of a pair of clamping members, a post attached to one of said clamping members, an oscillatory pawl or dog carried by said post and adapted to engage the inner surface of a casing, a casing having a serrated inner surface secured to the other of said clamping members and adapted to telescope over said post, an auxiliary

weight coöperating with said pawl or dog to lock the same in engagement with said casing, substantially as described.

5. In a binder, the combination of a pair of clamping members, a post attached to one of said clamping members, an oscillatory pawl or dog carried by said post and adapted to engage the inner surface of a casing, a casing having a threaded inner surface secured to the other of said clamping members and adapted to telescope over said post, means for rotating said post in said casing, an auxiliary weight coöperating with said pawl or dog to hold the same in engagement with said casing, substantially as described.

6. In a binder, the combination of a pair of clamping members, a post having a recess at the lower end thereof attached to one of said clamping members an oscillatory pawl or dog carried by said post in said recess and adapted to engage the inner surface of a casing, a casing secured to the other of said clamping members and adapted to telescope over said post, an auxiliary weight located in a chamber in said post coöperating with said pawl or dog to lock the same in engagement with said casing, substantially as described.

7. In a binder, the combination of a pair of clamping members, a post having a slot at the lower end thereof, an oscillatory pawl or dog pivotally attached to said post in said slot and having a portion thereof adapted to engage the inner surface of a casing, a casing secured to the other of said clamping members and adapted to telescope over said post, an auxiliary weight coöperating with said pawl or dog to lock the same in engagement with said casing, substantially as described.

8. In a binder, the combination of a pair of clamping members, a post having a slot at the lower end thereof, an oscillatory pawl or dog pivotally attached to said post in said slot having a portion thereof adapted to engage the inner surface of a casing and having a portion thereof adapted to engage an auxiliary weight to hold the same in position, a casing secured to the other of said clamping members and adapted to telescope over said post, an auxiliary weight coöperating with said pawl or dog to lock the same in engagement with said casing, substantially as described.

9. In a binder, the combination of a pair of clamping members, a post attached to one of said clamping members, an oscillatory pawl or dog pivotally attached to said post, having a portion thereof adapted to engage the inner surface of a casing and a portion thereof flattened to engage an auxiliary locking weight, a casing secured to the other of said clamping members and adapted to telescope over said post, an auxiliary weight coöperating with said pawl or dog to lock and hold the same in engagement with said casing, substantially as described.

10. In a binder, the combination of a pair of clamping members, a post attached to one of said clamping members, an oscillatory pawl or dog pivotally attached to said post, having a portion thereof adapted to engage the inner surface of a casing and a portion thereof adapted to be engaged by an auxiliary weight, a casing secured to the other of said clamping members and adapted to telescope over said post, an auxiliary weight coöperating with said pawl or dog to hold the same in engagement with said casing and adapted to drop out of engagement with the pawl when the clamping members are reversed in position thus rendering the pawl inoperative and allowing the clamping members to be separated, substantially as described.

11. In a locking device, the combination of a pair of telescoping members, an oscillatory pawl or dog carried by the inner of said members, an auxiliary weight carried by said inner member and so located in relation to said pawl as to lock the same in an operative position and adapted to drop out of engagement with said pawl when the members are reversed in position thus rendering the pawl inoperative and allowing the telescoping members to be separated, substantially as described.

12. In a binder, the combination of a pair of clamping members, a post having a slot at the lower end thereof, an oscillatory pawl or dog pivotally attached to said post in said slot, said slot having a portion thereof forming a stop to limit the movement of said pawl in one direction, an auxiliary weight located in a chamber adjacent to said slot in said post and adapted to limit the movement of said pawl in the opposite direction when the members are in one position and adapted to fall out of engagement with said pawl when the position of the members is reversed, a casing secured to the other of said clamping members and adapted to telescope over said post, substantially as described.

13. In a binder, the combination of a pair of clamping members, a post attached to one of said members, an oscillatory pawl or dog carried by said post and adapted to engage the inner surface of a casing, a casing secured to the other of said clamping members and adapted to telescope over said post, and an auxiliary member adapted to engage and lock said pawl or dog and adapted to fall out of engagement with the same when the binder is reversed.

14. In a binder, the combination of a pair of clamping members, a post attached to one of said members, an oscillatory pawl or dog carried by said post and adapted to engage the inner surface of a casing, a casing secured to the other of said clamping members, and adapted to telescope over said post, and an auxiliary member carried in a recess in said

post adapted to engage and lock said pawl or dog and adapted to fall out of engagement with the same when the binder is reversed.

15. In a binder-lock, in combination, a pair of telescoping members, an oscillatory pawl or dog carried by one of said members and adapted to engage the other of said members, and an auxiliary member adapted to engage and lock said pawl or dog and adapt-

ed to fall out of engagement when the device is reversed.

Signed at New York, in the county of New York and State of New York, this 16th day of June, A. D. 1905.

FREDERICK A. CLEVELAND.
